ARTICHOKE DISH

Mary E. Gorzelnik, 2504 Ming Road, Bakersfield, Calif.

Filed Mar. 14, 1960, Ser. No. 59,726

Term of patent 7 years

(Cl. D44—15)

FIG. 1

FIG. 3

Fig. 1 is a front perspective view of an artichoke dish showing my new design;

Fig. 2 is a rear perspective view; and

Fig. 3 is a transverse sectional view of Fig. 1.

I claim:

The ornamental design for an artichoke dish, as shown.
